UNITED STATES PATENT OFFICE

171,094

DESK STAPLER OR SIMILAR ARTICLE

Herbert W. Marano, Summit, N. J., assignor to Wilson Jones Company, Chicago, Ill., a corporation of Massachusetts

Application June 25, 1953, Serial No. 25,652

Term of patent 14 years

(Cl. D74—1)

To all whom it may concern:

Be it known that I, Herbert W. Marano, a citizen of the United States, and a resident of Summit, New Jersey, have invented a new, original, and ornamental Design for a Desk Stapler or Similar Article, of which the following is a specification, reference being had to the accompanying drawing, forming a part hereof, in which

Figure 1 is a top plan view of a desk stapler or similar article showing my new design;

I claim:

The ornamental design for a desk stapler or similar article, as shown.

HERBERT W. MARANO.
